US0D1057376S

(12) **United States Design Patent** (10) **Patent No.:** **US D1,057,376 S**
(45) **Date of Patent:** **** Jan. 14, 2025**

(54) **INSOLE**

(71) Applicant: **Yanfeng Zhao**, Shenzhen (CN)
(72) Inventor: **Yanfeng Zhao**, Shenzhen (CN)
(**) Term: **15 Years**
(21) Appl. No.: **29/965,996**
(22) Filed: **Sep. 30, 2024**
(51) LOC (15) Cl. **02-04**
(52) U.S. Cl. **USPC D2/961**

(58) **Field of Classification Search**

(57) **CLAIM**

The ornamental design for an insole, as shown and described.

DESCRIPTION

FIG. 1 is a front, right and top perspective view of an insole, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the insole that form no part of the claimed design.

1 Claim, 8 Drawing Sheets
